UNITED STATES PATENT OFFICE.

EMMIT G. LATTA, OF SYRACUSE, NEW YORK.

TYPEWRITING-MACHINE.

1,331,442.

Specification of Letters Patent. Patented Feb. 17, 1920.

Application filed February 23, 1917. Serial No. 150,328.

To all whom it may concern:

Be it known that I, EMMIT G. LATTA, a citizen of the United States, residing at Syracuse, in the county of Onondaga and State of New York, have invented a new and useful Improvement in Typewriting-Machines, of which the following is a specification.

This invention relates more particularly 10 to improvements in front strike or visible writing typewriting machines.

One object of the invention is to produce a visible writing or front strike typewriter equipped with a complete set of finger keys 15 in a full size keyboard, type-bars actuated thereby, and a platen and other co-operating parts, such as are usually employed in the standard makes of typewriters and in which all of the operative parts are mounted in 20 substantially constant relation on a single main frame which is adapted to be lowered from its operative position so as to occupy a comparatively small space for convenience in transportation.

25 Other objects of the invention are to provide the main frame with a movable or folding support which supports the main frame in an inclined operative position and is adapted to be moved to permit the frame to be lowered bodily from the inclined operative position to a recumbent position in which the machine occupies much smaller space; and also to improve typewriting machines in the other respects hereinafter described and set forth in the claims.

In the accompanying drawings:

Figure 1 is a side elevation of a typewriting machine embodying the invention, showing the same in the recumbent position 40 to which the machine is moved for transportation.

Fig. 2 is a longitudinal sectional elevation of the typewriter, showing the same in position for use, the supporting segment for the type-bars being indicated by broken lines and some of the type-bars and other parts being omitted.

Fig. 3 is a side elevation of the upper part of one of the rear supporting legs for the 50 machine.

Fig. 4 is a fragmentary plan view, partly in section, of the machine, some of the parts shown in Fig. 2 being omitted.

Fig. 5 is a sectional plan view of one side

of the frame and the supporting legs therefor, showing the legs in their folded or inoperative position.

The typewriting machine comprises, as usual in the standard makes of typewriters, finger keys A arranged in banks or rows, 60 preferably four rows at the lower front portion of the machine, the paper platen B journaled to rotate on a transversely movable carriage arranged at the upper rear portion of the machine at an elevation above 65 the keyboard, and the printing instrumentalities preferably comprising type-bars C pivoted in the usual segmental order and the connections whereby the type-bars are actuated by the operation of the finger keys. 70 Other parts of the machine, such, for instance, as the paper feed rolls D, the ribbon spools E, the paper table F, carriage escape- 75 ment wheel G, feed pinion H, and rack bar I on the carriage meshing with the feed pinion for controlling the letter space movements of the carriage, and the driving spring barrel K for the carriage are indicated in outline in the drawings to show their positions and relative arrangement in the machine. All these parts may be of usual or 80 well known construction so long as they are located between the planes indicated by the lines a—b and c—d in Fig. 2. They are mounted in the relative positions indicated 85 in the drawings and above briefly stated, on a single or rigid main frame which in the normal or operative position of the machine inclines upwardly and rearwardly with the rear portion of the frame and the platen and 90 other parts mounted thereon at an elevation above the keyboard, the frame being normally held in this position by a support which is adapted to be moved or folded to permit the main frame with the operative 95 parts carried thereby and retained in their normal relation, to be lowered bodily to a recumbent position, as shown in Fig. 1, whereby the machine is adapted to be placed in a carrying case of the small inside dimensions 100 indicated by the broken lines a—b—c—d in Fig. 1.

The main frame comprises side plates 1 and 2 rigidly connected, preferably by front and rear end bars 3 and 4 and an intermediate bar 5 which supports a guide or track 6 for the platen carriage. The bar 5 is preferably provided with rearwardly pro-

jecting brackets on which the carriage driving spring barrel K and escapement wheel G are mounted. One of these brackets is shown at 7, Fig. 2.

5 8 and 9 represent a pair of front legs or supports pivoted at their upper ends to the frame side plates 1 and 2, on the insides thereof, preferably by screws 10 and 11. 12 and 13 represent a complementary pair of rear legs or supports similarly pivoted to the side plates 1 and 2 by screws 14 and 15. The several legs shown have feet or cushions 16 of rubber or other suitable material permanently secured to their lower ends. The rear legs are longer than the front legs and the two pairs of legs are arranged in front and rear of the center of gravity of the machine. Stops, not shown, are provided to prevent the rear legs from 15 swinging farther to the rear than shown in Fig. 2, and the weight of the machine prevents forward movement of the legs in the use of the machine. The two front legs are rigidly connected to each other by a 20 cross rod 17 and are connected to the rear legs by a pair of links 18 and 19. The legs are thus retained in their relative positions and form a movable or folding support for the main frame, and are all caused to move 25 in unison when they are swung from their supporting position shown in Figs. 2 and 4 to the folded position shown in Figs. 1 and 5, and vice versa. The connecting links 18 and 19 are offset, as shown in Figs. 4 and 5, 30 to clear the feet of the rear legs when they are moved from one position to the other. A coil spring 20, see Fig. 3, is housed in the hub of each of the rear legs with one end 21 bent outwardly and entering a hole 35 in the adjacent side plate and the other end hooked into the leg as shown. These springs act to swing the legs downwardly and rearwardly to their supporting positions whenever the machine is lifted from the recumbent position shown in Fig. 1 to permit such 40 action. The springs assist the weight of the machine in holding the legs in supporting position. Obviously the pivoted legs forming the support may be made higher than 45 shown, or differently proportioned to give a desired inclination to the machine, or to fold backwardly instead of forwardly.

To lower the machine for close packing or convenience in moving, it can be pushed 55 rearwardly with one hand, while one of the rear legs is held by the other hand from sliding on the table. Then as the machine begins to move downwardly by its own weight it should be held against falling 60 down against the table. Another way is to turn the machine on one side and then fold the legs, after which the machine is turned over on its bottom, when its weight will hold it down with the legs folded. When 65 in the operative position shown in Fig. 2,

the highest part of the machine is approximately seven inches above the table top. This is so near the average height of standard machines in general use that it is not objectionably low for the operators of other 70 machines. The height of the machine when lowered is reduced to approximately three and one-half inches, and the complete machine can be packed in a rectangular case of the inside dimensions indicated in Fig. 1, 75 which is approximately only three-hundred and sixty-four cubic inches.

In order to permit the machine to be lowered as shown in Fig. 1, the type-bar segment is located very near the plane a—b of 80 the lower edges of the side plates 1 and 2, and the printing instrumentalities are arranged so that no fixed part of the key lever system projects below that plane. It is also desirable that the upper bank of keys 85 be near the free ends of the type-bars when the bars are at rest. These parts are preferably constructed and arranged as follows:

25, 26, 27 and 28 represent key stems consisting of sheet metal stampings of four different patterns, one for each of the four banks of keys. 29 indicates a series of arms pivotally mounted in a slotted bar 30 on a common pivot wire 31 and having their front ends pivoted to the key stems. 32, 90 33 and 34 represent a series of bell crank levers having forwardly projecting arms pivoted by shouldered rivets to the lower ends of the key stems, and upright arms connected by links 35 to the type-bars C. 100 The bell cranks are mounted in slots in the front side of a horizontally curved supporting bar 36 on a correspondingly curved pivot wire. The ends of the bar 36 are curved upwardly and outwardly to clear the 105 links 18 and 19 when the supporting legs are folded. This also facilitates machining the front side of the bar to admit the pivot wire. These bars 30 and 36 can be secured to the side plates of the frame in any suitable manner. In Fig. 2 only the three bell cranks for the lowest, the highest and an intermediate type-bar are shown. A series of 110 springs 37 connected to the bell cranks and to a metal strip 38 secured to the bar 30 115 act to restore the keys and connected parts to their normal positions.

The type-bars are pivoted in a slotted segment of usual form arranged as indicated by broken lines at 39 in Fig. 2, with 120 its plane inclined slightly to the rear so that the impressions are made slightly above the front center of the platen. The type-bars each have two characters and the segment is mounted on the free ends of arms 40 125 and 41 rigidly connected to rock shafts 42 and 43 to be shifted to upper case positions by depressing a key 44 on a shift lever 45 fixed to the rock shaft 42.

The upright arms of the bell cranks are of 130

graduated lengths increasing from the center toward the ends of the series, and in order to insure like action of the type-bars in both case printing positions of the segment, the pivots connecting the bell cranks to the links 35 are located in lines extending at right angles to the plane of the segment midway between the normal and shifted positions of the pivotal connections between the links 35 and the type-bars. As the front ends of the bell cranks are all pivoted to the key stems in the same vertical plane, their action on the type-bar is equalized by pivoting them, as before stated, on the horizontally curved bar 36 and graduating the lengths of their forward arms. If the bar 36 were curved enough to fully equalize the action of all of the bell cranks, the curvature of the bar would interfere with the proper action of the bell cranks near the ends of the bar, and to avoid this the bar is preferably curved as shown and the cranked ends of a few of the type-bars at the ends of the segment are made slightly longer than the others, so that the upper ends of the upright arms of the corresponding bell cranks may swing greater distances. In this way the desired movement of the type-bars is obtained with substantially equal depressions of the keys. Since the keyboard, which is of standard size, is wider than the type-bar segment, and it is desirable to have the links 35 extend in parallel lines from the bell cranks to the type-bars, the forward arms of most of the bell cranks are offset outwardly, and their upright arms inwardly, as shown in Fig. 4, the ends of the arms where pivoted to the key stems and to the links being parallel with these parts, and the fulcrum parts of the bell cranks being about midway between and parallel with the planes of their ends. The upright arms of a few of the bell cranks 32 at the middle of the series are curved as shown in Fig. 2 to clear the bar 30; the others are straight. The pivots connecting the key stems to the bell cranks are shown as being in the same horizontal plane with the pivots for the bell cranks in the bar 36. This applies power to the bell cranks to the best advantage, and produces a slight acceleration of motion. The connection of the links 35 to the type-bars also produces an accelerating motion of the type-bars in the usual way.

When the machine is lowered the heels of the central type-bars strike the table top and cause the segment and type-bars to rise to the upper case position. The type-bars then show above the side plates of the main frame and the shift key 44 is depressed as seen in Fig. 1.

While the above described construction and arrangement of the operative parts of the machine are desirable, other construc-

tions and arrangements thereof could be employed with the frame and its support constructed as described and set forth in the claims. The operative parts of the machine should, however, be arranged so that they are all located substantially between the plane *a*—*b* of the lower edges of the frame side plates 1 and 2, and a plane *c*—*d* parallel therewith and substantially tangent to the upper side of the paper platen, in order to enable the machine to occupy the smallest possible space when the support is folded or detached.

I claim as my invention:

1. In a typewriting machine, the combination with a rotatable platen, a series of independently movable type-bars, and a keyboard comprising finger keys for actuating the type-bars, of a frame on which all of said parts are mounted and which in its normal position supports the platen at the rear of the machine with its axis at a higher elevation than the type-bars and finger keys, said type-bars being movable to printing positions in a substantially upright plane at the front portion of the platen, said frame and said parts supported thereby being located between two substantially parallel planes which in the operative position of the machine incline upwardly and rearwardly from points adjacent respectively to the top and bottom of the keyboard, and a movable support which wholly supports said frame in an elevated operative position and is movable to permit the frame to be lowered bodily from such elevated position to a lower inoperative position.

2. In a typewriting machine, the combination with a rotatable platen, a series of independently movable type-bars, and a keyboard comprising finger keys for actuating the type-bars, of a frame on which all of said parts are mounted and which in its normal position supports the platen at the rear of the machine with its axis at a higher elevation than the type-bars and finger keys, said type-bars being movable to printing positions in a substantially upright plane at the front portion of the platen, said frame and said parts supported thereby being located between two substantially parallel planes which in the operative position of the machine incline upwardly and rearwardly from points adjacent respectively to the top and bottom of the keyboard, and a folding support which wholly supports said frame in an elevated operative position and is foldable to permit the frame to be lowered bodily from such elevated position to a lower inoperative position.

3. In a typewriting machine, the combination with a rotatable platen, a series of independently movable type-bars, and a key-

- board comprising finger keys for actuating the type-bars, of a frame on which all of said parts are mounted and which in its normal position supports the platen at the rear of the machine with its axis at a higher elevation than the type-bars and finger keys, said type-bars being movable to printing positions in a substantially upright plane at the front portion of the platen, said frame 10 and said parts supported thereby being located between two substantially parallel planes which in the operative position of the machine incline upwardly and rearwardly from points adjacent respectively to the top 15 and bottom of the keyboard, and front and rear pivoted supports which wholly support the frame in an inclined operative position and are movable to permit the frame to be lowered bodily from such elevated position 20 to a lower inoperative position.
4. In a typewriting machine having a platen, type-bars arranged to strike the front of the platen, and a keyboard, a main frame which supports said parts in substantially fixed operative relation to each other, and connected pivoted supports in front 25 and rear of the center of gravity of the machine which hold the frame in an elevated operative position and are adapted to be moved in unison to lower the frame bodily 30 from said elevated position to a lower position.
5. In a typewriting machine having a platen, type-bars arranged to strike the front of the platen, and a keyboard, a main frame which supports said parts in operative relation to each other, and front and rear pivoted supports of different lengths on each side of said frame adapted to be moved 35 to swing the main frame from an elevated upwardly and rearwardly inclined operative position to a substantially horizontal position.
6. In a typewriting machine having a platen, type-bars arranged to strike the front of the platen, and a keyboard, a single main frame which supports said parts in substantially fixed operative relation to each other, and front and rear pivoted supports 45 of different lengths on each side of the frame which hold the main frame in an elevated operative position free of the supporting surface with its rear end materially higher than its front end.
- 55 7. In a typewriting machine having a platen, type-bars arranged to strike the front side of the platen, and a keyboard, a main frame which supports said parts in substantially fixed operative relation to each other, folding front and rear supports on each side of the main frame, said rear supports being of greater length than the front supports, links connecting said front and rear supports and said front supports being 60 rigidly connected to each other, whereby all 65

of said supports are caused to move in unison.

8. In a typewriting machine having a platen, type-bars arranged to strike the front of the platen, and a keyboard, a main frame 70 which supports said parts in substantially fixed operative relation to each other, and front and rear pivoted supports for the main frame connected to move in unison inside of and parallel with the sides of the 75 main frame.

9. In a typewriting machine having a platen, type-bars arranged to strike the front of the platen, and a keyboard, a single main frame 80 on which said operative parts are mounted and retained in substantially constant relation to each other, and a support which rests on a supporting surface and wholly supports said main frame in an elevated inclined operative position free of 85 the supporting surface and is capable of movement from its normal position to permit the machine to move bodily and rest in a recumbent position with the lower edges of said main frame on said supporting surface. 90

10. In a typewriting machine having a rotatable platen, type-bars pivoted below the platen to strike the front of the platen, and a keyboard comprising actuating finger 95 keys for the type-bars, a single main frame on which said operative parts are mounted and retained in substantially constant relation to each other and substantially between the plane of the lower edges of the sides of 100 said frame and a parallel plane tangent to the upper side of the platen, and a support which wholly supports said main frame in an elevated operative position with said lower edges inclined upwardly and rearwardly and is capable of movement from its normal position to permit the machine to move bodily and rest in a recumbent position 105 on said lower edges of said main frame.

11. In a typewriting machine having a 110 rotatable platen, type-bars pivoted below the platen to strike the front of the platen, and a key-board comprising actuating finger keys for the type-bars, a single main frame on which said operative parts are mounted 115 and retained in substantially constant relation to each other, and a support which wholly supports said main frame in an inclined operative position and is capable of movement from its normal supporting position to a position substantially within the main frame to permit the machine to move bodily and rest in a recumbent position on the edges of said main frame. 120
